UNITED STATES PATENT OFFICE.

WILLIAM H. PERKINS, OF MERIDEN, CONNECTICUT, ASSIGNOR TO EDWARD MILLER & CO., OF SAME PLACE.

DESIGN FOR LAMP-STAND.

Specification forming part of Design No. 6,876, dated September 9, 1873; application filed June 4, 1873.
[Term of Patent 3½ years.]

To all whom it may concern:

Be it known that I, WILLIAM H. PERKINS, of Meriden, in the county of New Haven and State of Connecticut, have invented a new Design for Lamp-Stand; and I do hereby declare the following, when taken in connection with the accompanying drawing and the letters of reference marked thereon, to be a full, clear, and exact description of the same, and which said drawing constitutes part of this specification, and represents a front view.

This invention relates to a design for a support or stand for the bowl of a lamp; and consists in the form of the stand combined with the bowl and base, but irrespective of the form of the bowl or base.

A is the base, upon which rests a pedestal,

B, and upon this pedestal rests the bust of a female, a bird resting upon the right shoulder. Upon the head of the bust the bowl C of the lamp is set. The form of the bowl of the lamp is immaterial to this design, it only being essential that a bowl of some character be present.

I claim as my invention—

The design for lamp-stand, consisting of the bust and bird upon the base, the head of the bust supporting the bowl of the lamp, as herein described, and shown in the accompanying drawings.

WM. H. PERKINS.
